UNITED STATES PATENT OFFICE

JAMES H. THOMPSON, OF BLUEFIELD, WEST VIRGINIA, ASSIGNOR TO CLAUDE EDWARD GODSEY, OF BLUEFIELD, WEST VIRGINIA

FIGURE TOY

Application filed April 25, 1931. Serial No. 532,883.

This invention relates to figure toys, and more particularly to a toy which is adapted to be moved along a flat surface or the like.

An object of this invention is to provide a toy of this kind which is constructed so as to simulate a bird and particularly a wood-pecker mounted on a section of a tree, the device operating to cause the bird's head to strike the section of tree as the device is moved along a smooth surface.

Another object of this invention is to provide novel means for reciprocating the head of the bird, so as to cause it to strike a sound board or relatively hard object as the device is moved on a flat surface.

A further object of this invention is to provide a device of this kind which is relatively simple in construction, so that it may be readily and cheaply manufactured.

The above and various other objects and advantages of this invention will in part be described in and in part be understood from the following detailed description of the present preferred embodiment, the same being illustrated in the accompanying drawings, wherein:—

Figure 1 is a detail side elevation of a device constructed according to the preferred embodiment of this invention;

Figure 2 is a longitudinal section taken substantially through the middle of the device;

Figure 3 is a sectional view taken on the line 3—3 of Figure 2, with the pulley shown in plan view;

Figure 4 is a sectional view taken on the line 4—4 of Figure 2;

Figure 5 is a sectional view taken on the line 5—5 of Figure 2, with the pulley and wheels in plan view, and

Figure 6 is a sectional view taken on the line 6—6 of Figure 2.

Referring to the drawings wherein like numerals of reference designate corresponding parts throughout the several views, the

numerical 10 designates generally an elongated body member which is of tubular construction and provided at the upper end thereof with a plug 13 within which an elongated handle 11 is mounted. The handle 11 is 50 preferably disposed longitudinally of the tubular body 10, and the lower end of the body 10 is provided with opposed alined bearings 12, which are constructed in the form of metal eyelets which are crimped on 55 the tubular body 10, this body 10 being of cardboard, or the like construction. A shaft 14 is rotatably mounted in the bearings 12, and wheels 15 are secured to the shaft 14, the wheels 15 being disposed on opposite sides 60 of the body 10. This body 10 is cut on an angle at the upper end thereof, as at 16, and the periphery of the body 10 is painted or otherwise formed so as to substantially simulate the trunk of a tree. 65

A figure, generally designated as 17, is mounted on the periphery of the trunk 10 intermediate the ends thereof, this figure 17 in the present instance being constructed so as to simulate the figure of a woodpecker, or 70 the like. The figure 17 comprises a fixed body portion 18 which is of hollow construction, and is provided with an extension 19, which is disposed within the tubular body 10, this extension 19 being secured to the 75 body 10 by means of glue, tacks or the like. The body 18 of the figure 17 is also provided with an upwardly extending portion 20, which is disposed within the trunk member 10, and is secured thereto by means of tacks 80 or glue, this upwardly extending portion 20 constituting a sound board, the purpose for which will be hereinafter described. A tail 21 is secured to the lower end of the body 18 and is of a configuration to simulate the 85 tail of the bird 17.

The trunk 10 is provided with an elongated slot 22 which communicates with the interior of the figure body 18 and a head 23 is rockably mounted in the body 18 and 90

extends upwardly therefrom, this head 23 having a beak 24 which is shaped to simulate the beak of the bird 17. The head 23 is provided with trunnions 25 on the opposite sides thereof, which extend through the sides of the body portion 18, and wing members 26 are secured to the outer ends of the trunnions 25 and are adapted for movement therewith and with the head 23. A driven pulley 27 is rotatably carried by a reinforcing block 28 mounted within the trunk 10, the pulley 27 being rotatably mounted on a headed shaft 29, the head of which is preferably countersunk in the body of the pulley 27.

15 An outstanding pin or screw 30 is carried by the pulley 27 at a point offset from the center thereof, this pin 30 constituting a crank, and the head 23 has a screw eye 31 mounted in the lower end portion thereof.

20 A connecting link 32 is provided at each end thereof with eyes formed integrally therewith, and one eye is rotatably mounted on the pintle or crank pin 30, and the opposite end is mounted on a rivet 33 so that when

25 the pulley 27 rotates on the shaft 29, the head 23 will reciprocate therewith. A drive pulley 34 is mounted on the drive shaft 14, and a flexible member 35 is trained over the drive pulley 34 and the driven pulley 27. In this

30 manner, as the wheels 15 rotate, the pulley 27 will rotate and the head 23 reciprocate so as to simulate the operation of a wood-pecker cutting a hole in a tree.

35 A headed tack 36, or the like, is disposed through the trunk 10 and extends into the sound board 20, the head of the sounding member 36 being relatively large and disposed in the path of the free end of the beak 24. In this manner, the beak 24 will strike

40 the head of the member 36 and simulate the sound of a woodpecker cutting a hole in the trunk of a tree. The wheels 15 may be provided with tread members 37, so as to facilitate the rotation thereof over a smooth surface. The lower end of the trunk 10 is preferably closed by a cap 38, which is provided with a substantially semi-spherical surface terminating in a tubular portion 39 which engages the inner surface of the trunk 10,

45 the tubular portion 39 being provided with a slot 40 so that the inner end of the tubular portion 39 can pass the shaft 14.

50 In the operation of this device, the handle 11 may be grasped in the hand and the trunk 10 disposed forwardly of the individual. In the movement of the trunk 10, the wheels 15 will rotate and coercively rotate the drive pulley 34 and the driven pulley 27 through the flexible member 35. The rotation of the driven pulley 27 will reciprocate the head 23, so that the beak 24 will strike the outer surface of the tack or headed member 36. Preferably, the driven pulley is smaller in diameter than the drive pulley 34, so that

55 when the device is moved over the ground at

a relatively slow rate, the head 23 will reciprocate at a relatively rapid rate.

It is, of course, understood that various changes and modifications may be made in the details of construction and design of the above specifically described embodiment of this invention without departing from the spirit thereof, such changes and modifications being restricted only by the scope of the following claims.

I claim:—

1. A figure toy of the character described comprising an elongated hollow body, a drive shaft carried by the body, wheels mounted on the drive shaft, a figure mounted on the outer surface of the body, said body having an opening in a wall thereof, said figure having a fixed portion and a rockable portion, means for securing said fixed portion in a position to overlie the opening, a driven member mounted in the body and engaging the rockable portion, a drive member mounted on the shaft, and means connecting the driving member with the driven member said securing means including oppositely extending portions formed with the figure and disposed inwardly of the body.

2. A figure toy of the character described comprising an elongated hollow body having an opening in a wall thereof, a drive shaft rotatably mounted in the body, wheels carried by each end of the drive shaft and disposed outwardly of the body, a handle for the body, a figure toy mounted on the body inwardly from each end thereof, said toy comprising a hollow fixed portion and a rockable portion, means for securing said fixed portion in a position to overlie the opening, a drive pulley mounted on the drive shaft within the body, a driven pulley, link means connecting the driven pulley with the rockable portion, and flexible means engaging the drive pulley and the driven member for rotation thereof coercive with the rotation of the wheels said securing means including oppositely extending portions formed with the figure and disposed inwardly of the body.

3. A figure toy of the character described comprising an elongated hollow body having an opening in a wall thereof, a plug carried by one end of the body, an elongated handle mounted in the plug and extending upwardly from the body, a drive shaft disposed transversely through the opposite end of the body, wheels mounted on the shaft, a figure carried by the body inwardly from each end thereof, said figure having a hollow fixed portion and a rockable portion, means for securing said fixed portion in a position to overlie said opening a driven pulley mounted within the body beneath the figure, connecting means connecting the driven pulley with the rockable portion whereby to rock said rockable portion upon rotation of the pulley, a drive pulley mounted on the shaft

within the body, a flexible member connecting the drive pulley with the driven pulley, and means disposed in the path of the rockable portion whereby to contact therewith upon rocking of the rockable portion said securing means including oppositely extending portions formed with the figure and disposed inwardly of the body.

In testimony whereof I hereunto affix my
10 signature.

JAMES H. THOMPSON.
